Primary Examiner — Karen E Eldridge Powers(74) *Attorney, Agent, or Firm* — Dale J. Ream(57) **CLAIM**

The ornamental design for a hooded garment, as shown and described.

DESCRIPTION

FIG. 1 is a front/right side perspective view of a hooded garment showing my new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

In the drawings, the broken lines showing a mannequin illustrate environment and form no part of the claimed design.
